UNITED STATES PATENT OFFICE.

HUBERT MILTON GREIST, OF NEW HAVEN, CONNECTICUT, ASSIGNOR TO THE GREIST MANUFACTURING COMPANY, A CORPORATION OF CONNECTICUT.

BLOTTER.

1,135,012.

Specification of Letters Patent. Patented Apr. 13, 1915.

Application filed March 9, 1914. Serial No. 823,416.

To all whom it may concern:

Be it known that I, HUBERT M. GREIST, a citizen of the United States, residing at New Haven, in the county of New Haven and State of Connecticut, have invented or discovered certain new and useful Improvements in Blotters, of which the following is a specification, reference being had therein to the accompanying drawing.

- 10 In signing a large number of checks, or the like, as is frequently necessary, busy business men are put to considerable inconvenience and delay, resulting from blotting the same after making each signature, and 15 particularly so where the circumstances are such that the pen must be laid down and the blotter applied by the right hand of the signer while the left hand is holding the checks.
- 20 This invention has for its object to provide an improved blotter which will automatically lift itself after having been depressed for the purpose of blotting a signature, the construction being such that a depression of the blotting pad may be effected 25 by the right hand of the signer, while still holding the pen therein, or the blotting pad may be depressed by the left hand while the right hand may hold the checks while still 30 retaining the pen.

To this end the improved blotter comprises a table or plate which is preferably of metal of sufficient thickness and weight to stand steadily in place. To this table or 35 plate, on which a pile of checks to be signed may be laid, is preferably secured a sleeve in which is journaled a rod preferably having two bent arms extending forward therefrom, one of said arms, carrying a blotting 40 pad and the other being provided with a knob or hand piece by which the blotting pad may be depressed after a check has been signed, and which blotting pad will be automatically lifted, after having been depressed, by a suitable spring.

In the accompanying drawing Figure 1 is a perspective view of the improved blotter with the blotting pad lifted. Fig. 2 is a plan view, and Fig. 3 a front view of the same, 50 with the blotting pad depressed.

Referring to the drawing, 12 denotes a plate or table which is preferably of metal and of sufficient thickness to be heavy enough to stand steadily in place. To the

rear edge of said plate or table, in the form 55 of the invention herein shown, is soldered or otherwise suitably affixed a sleeve 13 within which is journaled a rod 14 preferably provided with two forwardly extending arms 15 and 16.

To the arm 15 is attached the blotting pad preferably consisting of a plate 17 to which is affixed a post 18 threaded at its upper end for the reception of a nut 19, the said post passing loosely through any one of several 65 holes 20 with which the forward end of the arm 15 is preferably provided, so that the blotting pad may be secured in different positions of adjustment, if desired, to permit different portions of the blotting paper 21, 70 forming a part of the blotting pad, to be brought into different positions by an adjustment of the said pad on said arm. The blotting paper is held in position on the pad by means of a resilient metal clamping plate 75 22 interposed between the nut 19 and the forward end of the arm 15.

The construction just described affords means whereby the pad is pivotally attached to the arm 15 and may therefore be swung 80 sidewise to different positions, if desired. The arm 16 is preferably provided with a knob 23 for conveniently depressing the blotting pad.

Coiled around the rod 14 is a torsional 85 lifting spring 24 by which the blotting pad will be automatically lifted after each depression thereof, the lifting movement of the said pad, under the influence of said spring, being limited by a stop, consisting, 90 in the present instance, of a pin 25 on the rod 14, and which is arranged to engage a portion of the plate 12.

From the foregoing it will be understood that in signing checks, a pile of which may 95 be laid on the plate or table 12, it will only be necessary, after making each signature, for the signer to depress the blotting pad either by pressure on the knob 23 or otherwise, and as soon as the pressure is relieved 100 the blotting pad will be automatically lifted out of the way of the signer, leaving the checks or other papers to be signed unobstructed for the next signature.

While it is preferred to provide the pivoted rod 14 with the arm 16 having the depressing knob 23, it will be understood that this arm 16 is not positively necessary, and

might be dispensed with; and in such case the pressure to depress the blotting pad may be applied directly thereto or to the arm 15.

Having thus described my invention I 5 claim and desire to secure by Letters Patent:

1. A blotting device consisting of a plate or table, a rod having a journaled connection with the rear part of said plate or table 10 and provided with an arm extending forwardly over said plate or table, a blotting pad attached to said arm over said plate or table, a spring for lifting said blotting pad after the same has been depressed, and 15 means for limiting the lifting movement of the blotting pad by said spring.

2. A blotting device consisting of a plate or table, a rod having a journaled connection with the rear part of said plate or 20 table and provided with an arm extending forwardly over said plate or table, a blotting pad adjustably attached to said arm over said plate or table, a spring for lifting said blotting pad after the same has been 25 depressed and means for limiting the lifting movement of the blotting pad by said spring.

3. A blotting device consisting of a plate or table, a rod having a journaled connection with the rear part of said plate or 30 table and provided with two arms extending forwardly over said plate or table, a blotting pad attached to one of said arms over said plate or table, a knob attached to 35 the other of said arms, a spring for lifting said blotting pad after the same has been depressed, and means for limiting the lifting movement of the blotting pad by said spring.

4. A blotting device consisting of a plate or table, a sleeve attached to the rear part 40

of said plate or table, a rod journaled in said sleeve and provided with an arm extending forwardly over said plate or table, a blotting pad attached to said arm over said 45 plate or table, a torsional spring for lifting said blotting pad after the same has been depressed, said spring being coiled around a portion of said rod outside of said sleeve, and a stop on said rod for limiting the lifting 50 movement of said pad by said spring.

5. A blotting device consisting of a plate or table, a sleeve attached to the rear part of said plate or table, a rod journaled in said sleeve and provided with an arm extending forwardly over said plate or table, a blotting pad pivotally and adjustably attached to said arm, a torsional spring coiled around said rod, for lifting said blotting pad after the same has been depressed, and 60 a stop on said rod for limiting the lifting movement of said pad by said spring.

6. A blotting device consisting of a plate or table, a sleeve attached to the rear part of said plate or table, a rod journaled in 65 said sleeve and provided with two arms extending forwardly over said plate or table, a blotting pad pivotally and adjustably attached to one of said arms, a knob carried by the other of said arms, a torsional 70 spring coiled around said rod, for lifting said blotting pad after the same has been depressed, and a stop on said rod for limiting the lifting movement of said pad by said spring.

In testimony whereof I affix my signature, in presence of two witnesses.
